(57) **CLAIM**

The ornamental design for a dual chamber food jar, as shown and described.

DESCRIPTION

FIG. 1 is a perspective view of a dual chamber food jar showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the dual chamber food jar shown in an open position thereof;

FIG. 9 is a left side elevational view thereof; and,

FIG. 10 is a right side elevational view thereof.

The broken lines immediately adjacent to claimed subject matter shown in FIGS. 1, 4, 5, 7, 8, 9, and 10 represent portions of the dual chamber food jar that form no part of the claimed design.
